UNITED STATES PATENT OFFICE.

GUSTAVUS S. ALDEN, OF DENVER, COLORADO; CLARISSA B. ALDEN
ADMINISTRATRIX OF SAID GUSTAVUS S. ALDEN, DECEASED.

NEWSPAPER FOLDING, WRAPPING, ADDRESSING, AND BINDING MACHINE.

SPECIFICATION forming part of Letters Patent No. 389,629, dated September 18, 1888.

Application filed May 25, 1885. Serial No. 166,784. (No model.)

To all whom it may concern:

Be it known that I, GUSTAVUS S. ALDEN, a citizen of the United States, residing at Denver, in the county of Arapahoe and State of Colorado, have invented a new and useful 5 Newspaper Folding, Wrapping, Addressing, and Binding Machine, of which the following is a specification.

My invention relates to improvements in 10 folding and wrapping machines in which a folding-blade forces the paper and wrapper into the bite of two parallel revolving rollers to accomplish the various folds; and the objects of my improvements are, first, to convey 15 a newspaper or periodical, after it has been reduced to a suitable size by an ordinary folding-machine, and an associated wrapper, through a continuous series of mechanical devices, whereby the newspaper or periodical is 20 enveloped by the wrapper, and the two forming a wrapped and sealed product ready to be addressed; second, to afford a means of placing upon each sealed product an individual address; third, to afford a means of binding up 25 into a complete package any desired number of products, and imparting to the last, or outside one, the name of the post-office for which the package is intended. I attain these objects by the mechanism illustrated in the accompanying drawings, forming a part of this 30 specification, in which similar figures refer to similar parts throughout the several views.

Figure 1 is an end view of the entire machine. Fig. 2 is a partial section of the upper 35 portion of Fig. 1, taken in a line parallel with the movement of the traveling tapes and at or near the central part of the machine. Fig. 3 is a sectional diagram of the middle portion of Fig. 1, taken in a plane at right angles to the 40 section-plane of Fig. 2 and showing the devices which impart to the associated paper and wrapper their first and second folds, a pasting device, a turning device, which arrests and turns over between the upper 45 and lower tapes the folded and partially-wrapped paper and a pair of final-pressing rollers, from which it drops a wrapped and sealed product. Fig. 4 is a detached view of mechanism shown in part in Fig. 3, which 50 turns the associated paper and wrapper over between the tapes. Fig. 5 is a plan view of

the same. Fig. 6 is an enlarged side view of the mechanism used to convey the paper to the point B, (see Fig. 2,) where it is associated with the wrapper, the parts being in reverse 55 position to what the corresponding parts are in Fig. 2. Fig. 7 is a plan view of Fig. 6. Fig. 8 is a top view of the feed-board. Fig. 9 is a detached sectional view of a portion of the machine. Fig. 10 is a front view of the 60 plunger 51, showing the openings in the same. Fig. 11 is a plan view of parts shown in Fig. 9. Fig. 12 is a side view of the addressing-chain. Fig. 13 is the pin used in joining the links of the chain together. Fig. 14 is a top 65 view of the chain joined together, showing, also, elongated link 69. Fig. 15 is a back view of the plunger 51, showing the mechanism which operates the addressing-chain and the device which brings the binder into operation. 70 Fig. 16 is a front view of the plunger 51, showing the position of elongated link 69 when about to impart an address to a package. Fig. 17 is a detached view of a portion of the binding mechanism on an enlarged scale. Fig. 18 75 is a plan view of a portion of the mechanism shown in Fig. 17, and Fig. 19 is a plan in detail of the grippers shown in Fig. 18. Fig. 20 shows the relative position of the wrapper and paper immediately after they have been associated at B, Fig. 2. Fig. 21 shows their relative position after receiving their first fold at A, Fig. 2. Fig. 22 shows their relative position after having received their second fold and paste. Fig. 23 is a wrapped and sealed 80 paper. Fig. 24 is a complete package of wrapped and addressed papers.

In Fig. 1 band-wheel 159 is located on the end of shaft 7, on the opposite end of which is gear 151, which meshes into gear 152 on the 90 end of cutting-cylinder 19, which has also a small gear, g, that meshes into one of equal size (not shown) on shaft of cutting cylinder 20. (Shown in Fig. 2.) Gear 151 also meshes with an intermediate gear, which in turn meshes 95 with gear 153 on the end of tape-pulley shaft 11. The balance of the tape pulleys shown in Fig. 2 are turned by the tapes themselves. Shaft 7 also has beveled gear 154, which turns beveled gear 155 on shaft 156, which has on 100 its opposite end beveled gear 157, meshing with beveled gear 158 on shaft 159, to which is at-

tached crank-wheel 56, which also serves the purpose of a gear-wheel and meshes with crank-wheel 37 on the end of shaft 160, which has on its opposite end gear 161, which drives 5 the chain of gears 32', 30', 29', 27', and 26', the latter, which meshes with gear 27', being turned by intermediate gear 162, gear 26' being double width to enable it to mesh with both gears 27' and 162. The turning mechanism on arm 10 35 is given a horizontal motion by crank-wheel 37. Crank-wheel 56 gives a similar motion to arms 52, which carry the addressing mechanism. Folding-blades 23 and 50 are operated by cams 25 and 32, located on shaft 7. Drop- 15 rolls 4 (see Fig. 6) are raised and lowered by cam 6 on shaft 7. I have thus described the manner in which the principal parts of my machine receive their operating power.

In Fig. 2, 21 is a web of wrapping-paper 20 reeled on spool 18, mounted in bearings in the frame. 19 and 20 are male and female cutting-cylinders, one provided with a cutting-knife and the other slotted in such a manner that the web will be severed with each revolution 25 of the cylinders. The circumference of either is equal to the width required for one wrapper. 13 is a series of short endless tapes passing around drop-rolls 4 and tape-wheels 1, which are loose on shaft 164. 14 is a series of endless 30 tapes passing around tape-wheels 9, 10, 11, 12, 15, 16, and 17. 8 is a series of endless tapes which pass over rolls 3, under tape-wheels 1 and 9, and over 10, 11, and 12. These three sets of tapes are driven continuously at a uniform speed 35 by tape-wheels 11, as heretofore described. 2 is a feed-board with an opening cut away at the lower end (see Fig. 8) to allow the operator to grasp the folded edge of the paper to be operated upon between his thumb and fingers. 40 4 are drop-rollers (see Fig. 6) with bearings in arms 5, fastened to shaft 164. 3 is a roller cut away in the center. This combination, it will be seen, makes it possible for the operator to grasp a paper by its forward edge and 45 convey it forward under the drop-rollers 4, which, being operated by their cam, as described, descend and the paper is caught between the upper and lower tapes, 13 and 8, and conveyed forward.

50 It will be observed (see Fig. 2) that the paper is carried by the lower series of tapes only, for the distance between tape-wheels 1 and 9 is so short that it will have reached tape-wheels 9 before it has been released from the pressure 55 of tape-wheels 1.

The distance from the bite of cutting-cylinders 19 and 20 to the lower extremity of tape-wheels 9 is equal to the width of paper required for one wrapper, and the movement of 60 the said cylinders is so timed that the leading end of the wrapper-web will reach the bite of tape-wheels 9 and tapes 8 simultaneously with the forward edge of the newspaper, and, the web being severed, the newspaper and wrapper thus formed enter between tapes 14 and 8 and are conveyed forward together, the wrapper being on top with one end projecting be-

yond the side of the paper and in the relative position shown in Fig. 20 as they move forward in the direction shown by the arrow. 70 Thus they are conveyed around tape-wheels 10 and 11 and to adjustable stop 22, the wrapper now being below the paper. The wrapper and paper are now forced into the bite of rolls 26 and 27 by folding-blade 23, thus accomplishing their first fold. (See Fig. 3.) The relative position of the paper and wrapper at this time is shown in Fig. 21.

In Fig. 3 the associated wrapper and paper are conveyed forward from rolls 26 27 by endless tapes 28 and shot across and over the bite of rolls 29 and 30 and under folding-blade 50. They are now forced into the bite of rolls 29 and 30, receiving the second or last fold, and during their passage through these rollers two 85 (or more) parallel lines of paste are deposited upon the portions of the wrapper indicated in Fig. 22 in the following manner: At suitable distances apart the roll 30 is cut away, and segment-wheels 31, the faces of which are flush 90 with the surface of roll 30, are attached to the shaft in lieu of the parts cut away. The paste is deposited upon segment-wheels 31 by paste-wheels 32, which revolve in fountain 33. The paste being deposited on the surface of segment-wheels 31 is by them imparted, as it passes between 29 and 30, to the portions of the wrapper as before shown, or upon a greater or less portion, as is found necessary, to properly secure the flap to the main wrapper. This 95 may be regulated by the width or number of segment-wheels 31. The surface of roll 29 is also cut away at the points opposite segment-wheels 31, so that should any paste escape from said wheels it will not be deposited on 100 the surface that presses against the reverse side of the wrapper. The partially wrapped and pasted product is now carried forward between tapes 28 and 34, the flap or pasted end being on top and to the rear of the paper. In this condition they are conveyed into the jaws 45 or 46, which, by means of their operating mechanism, move forward and at the same time accomplish a half-turn between the 105 tapes, the rear end of the wrapper being held 110 against the upper tapes during the operation of turning. By the time jaws 45 or 46 have completed their half-turn the product will again be in a horizontal position, as before, except that the rearward edge will be the leading one, and the tapes, being released from the strain upon them, resume their former 115 relative position, and in so doing press down the pasted flap to the main wrapper. From this point the product is carried on by the 120 said tapes and is passed between rolls 47 and 48, which give it a final pressure, and the wrapped and sealed product drops onto flat bars 49.

The mechanism that operates jaws 45 and 125 46 is shown in Figs. 4 and 5, consisting of arm 35, with bearing in cross-bar 36, which has a horizontal motion imparted by crank-wheel 37, as before described.

38 is a small shaft with bearings in the forked ends of arm 35. It is placed between tapes 28 and 34, and has fastened to it jaws 45 and 46, each of which receives and disposes of a paper 5 alternately. On the end of shaft 38 is gear-wheel 39, which meshes with gear 40, (on pin 38,) double the size, which moves simultaneously with ratchet-wheel 41 on the same pin, which is turned, as it moves forward, by pawl 10 42 on arm 43, to the end of which is attached a friction-wheel, which works in the rigid slotted guides 44, attached to the main frame. As shaft 35 moves forward, pawl 42 gives ratchet-wheel 41 a quarter-turn, which moves gear-wheel 40 a like distance, and gear 39, being one-half the size, receives a half-turn, which turns jaws 45 and 46, containing the paper and wrapper, as before described, and, returning, the opposite set of jaws receive the next paper 20 and dispose of it in the same manner.

In Fig. 14, 62 is an addressing-chain composed of a series of links hinged together by pin shown in Fig. 12, which is so constructed that the two ends may be sprung apart and 25 the straight side of the pin inserted into the eyes of the hinges to be joined together, and after it has been passed through the said eyes the bent end will be allowed to spring back and prevent the pin from slipping out unless 30 removed by human or some unusual agency. The hinges are toothed at either end and are of uniform size, excepting the one used for the last one of a number of addresses all destined for one post-office. Link 69 is an elongated 35 link, to one half of which is attached an individual address and to the other or extended half the address of the post-office for which a certain number of papers are intended. The teeth on the ends of the links make it possible 40 when they are joined together to operate the chain by a continuous or step-by-step motion by means of a chain-wheel or equivalent power. The elongated link 69 also serves to trip the 45 binding mechanism and bring it into operation, as will be hereinafter shown. Addressing-chain 62 is wound around reel 58, (see Fig. 1,) with bearings on the upper sides of shafts 52. 59 is a similar reel with bearings on the lower sides of the same shaft. It is 50 provided with a coil-spring (not shown) to take up the slack of the chain. The chain 62 passes from reel 58 around chain-wheels 60, (see Fig. 9,) attached to shaft 72, which has its bearing in arm 122, attached to plunger 51. 55 They are so placed that the chain in passing around them will protrude a trifle through the opening N in plunger 51, cut for the purpose, and shown in Fig. 10. Plunger 51 is attached to the ends of shafts 52, which have a 60 horizontal motion imparted by crank-wheel 56, as before described. Thus the plunger which pushes the wrapped paper forward and the addressing-chain with its operating mechanism are all carried forward and backward by shafts 52. 65 The wrapped and sealed paper having dropped on its edge onto flat bars 49, as heretofore described, it is pushed forward by plunger

51 past the yielding stops 123, (see Fig. 11,) which allow the paper to pass them; but the moment it has passed they spring back into position and prevent it from returning or falling back, although plunger 51 may return by reason of two openings, *h h*, (see Fig. 10,) cut in its ends. As the wrapped paper is thus forced into packing-box 57 (see Fig. 9) it receives an 70 address from chain 62, which has been previously inked by ink-charged roller 121, with bearings in the upper ends of arm 122. Chain 62 is led forward with a step by step motion by chain-wheels 60, which are operated automatically and remain inoperative unless a paper is being pushed forward by plunger 51. Attached to shaft 63 are pawl 64 and cam 65. An opening, *i*, is cut in plunger 51, which permits it in its horizontal motion to pass pawl 85 64 without coming in contact with it; but if a paper is in front of it the paper closes the aperture *i* and causes pawl 64 to assume a horizontal position, bringing cam 65 on the same shaft up so that friction wheel 66 on the 90 end of lever 67 encounters it, and ratchet-wheel 68, fastened to shaft 72, is moved forward one tooth by the pawl attached to lever 67 and a new address brought into position. Thus chain 62 is moved forward in the same 95 manner until the desired number of papers to be included in a certain package have all been deposited and addressed except one. The last name in a package is attached to an elongated link, 69, which imparts simultaneously to the 100 last or outside paper the name of an individual, and apart from this the name of the post-office for which the package is destined. The binding apparatus is brought into operation at this time in the following manner: During the passage of chain 62 around chain wheel 60 link 69 engages with the single tooth 71 on the end of drum 70, (see Fig. 15,) which is loose on shaft 72, and turns the drum forward as the chain advances. As double link 69 is 105 brought into position the bevelled cam 73 on the opposite end of drum 70 operates lever 74, which causes it to release bolt 75, which is forced downward by spring 76, and as plunger 51 returns bolt 75 engages with endless 110 chain 78, which passes around chain-wheels on shafts 79 and 63, chain-wheel being loose on the latter. (See Fig. 9.) The links of endless chain 78 are of such a size that by the time plunger 51 shall have completed its backward stroke it will have given shaft 79 one 115 complete turn, which furnishes the power that operates my binding apparatus. A ratchet and pawl, *x* and *y*, attached to shaft 79, prevent chain 78 from moving except in one direction. 120

The lower end of bolt 75 is beveled, as are also the bars or links of chain 78, so that when plunger 51 starts forward the friction of chain 78 upon the beveled edge of bolt 75 forces same bolt back to its original position, where 125 it is held by arm 74 until again operated on in a similar manner to that just described.

It should be noted that as plunger 51 moves forward, carrying a folded paper before it, le-

ver 64 is operated, lifting cam 65 and advancing chain 62 a single link, the other parts operating in the manner already described. The drum carrying chain 78 and mounted on the shaft geared with the shaft-rotating arm 81 does not turn as the chain moves forward, by reason of the pawl x and ratchet y preventing rotation of said drum by any forward movement of the bolt 78; but upon the retreat of the plunger 51 the chain moves with it, rotating the drum and shaft and imparting movement to the arm 81. The forward movements of the plunger are repeated until the chain has so far advanced as to bring the double link 69 against the tooth 71 on the drum 70, Fig. 15, whereby the drum is rotated far enough to bring one of the cams 73 against the friction roll on the end of catch 74 and release the latter from belt 75, which is at once thrown down by spring 76. The drum 70 now stands in this position, holding the catch back, and the bolt 75 rides over the projections on the belt 78, and on the rearward stroke of the plunger it carries the belt with it, turning the arm 81, as already set forth. Now, as the plunger 51 again moves forward, carrying the next folded paper, the chain 62 is advanced a single step, carrying the drum 70 far enough to ride the friction roll on catch 74 off the cam 73 on the drum, thereby releasing the catch, which springs back into position to engage the bolt. As the latter encounters the beveled pieces on chain or belt 78 it is raised to position to engage catch 74, and remains in engagement therewith until the operation is repeated by the recurrence of a second double link, 69, in the chain 62.

In Fig. 9, 81 is a hollow arm on the end of shaft 82, to which is attached a spool of wire, 83, 40 which is fed through the bent point of arm 81.

94 in Fig. 17 is an arm to which is attached a pair of grippers, 94' and 94", at either end. Arm 94 is attached to the end of horizontal shaft 92, with bearing in frame 139. Their normal position is horizontal and transversely across the packer-box, one pair being open and the other closed and holding the end of the wire which emanates from the point of arm 81. It will thus be seen that the wire is stretched in a vertical position, a little to one side of the center of packer-box 57 (see Fig. 9) and directly in the path of plunger 51, which, by means of the paper in front of it, presses against the wire, the end of which is firmly held in grippers 94'. As the wrapped and addressed papers accumulate in the packer they press against the wire, which gradually encircles them on the top, forward, and lower sides, as shown, until the entire number to be included in a certain package have been so deposited in the packer, and it remains to sever the main wire at a suitable place, associate the end thus formed with the one held in grippers 94', and twist the two together.

65 Shaft 82 has beveled gear 119, which meshes with beveled gear of equal size, 120, on the end of shaft 79, and the single turn given to shaft

79 by endless chain 78, as heretofore described, causes shaft 82, with hollow arm 81, to make one complete revolution. Flat bars 106 are hinged to bars 49 by pin 107, to which is attached, also, pawl 108, which, being operated upon by cam 109 on shaft 82, causes bars 106 to assume a vertical position during the time arm 81 is making its revolution, after which they spring back to their horizontal position by means of a spiral spring on pin 107. On the opposite end of shaft 79 is a beveled gear (not shown) meshing with one of equal size (not shown) on the lower end of shaft 84. Beveled gear 85 on the upper end of said shaft and beveled gears 86 and 88 on either end of shaft 87 complete the chain of gearing, which gives beveled gear 89 and shaft 90, to which it is attached, one complete revolution simultaneously with shaft 82. Attached to shaft 90 is beveled gear 91, which meshes with beveled gear 93, twice the size, as shown in Fig. 17, on the end of shaft 92, which carries arms 94 on its opposite end, which consequently receives a half turn simultaneously with the complete revolution of arm 81. By the time the bent point of arm 81, from which the wire is being fed, reaches the highest point in its revolution, arm 94 will have made a quarter-turn and will be in a vertical position, as shown in Fig. 17. The grippers that have heretofore held the end of the wire having now deposited the same in one end of twisting-grippers 95, attached to the end of shaft 92, and arm 81, from which the main wire is being fed, having deposited the wire in the other end of the same grippers, 95, friction-wheel 89, fastened to arm 81, operates upon cam 100 and closes grippers 95, which as they are closed sever the wire by means of shears 99 (see Fig. 18) on the upper sides of their outer ends. Grippers 94', which have heretofore held the end of the wire, are now released from the control of rigid cam 110, attached to frame 139, (see Fig. 17,) and are sprung open. The opposite pair of grippers at the same time pass under the control of cam 110 and are closed upon the main wire, which has been deposited in them at the same time that it is severed by shears 99, and hold it, still moving on until they reach a horizontal position again, where they retain it in readiness for the next bundle of papers, arm 81 having completed its revolution, and the wire is again stretched vertically in the path of plunger 51, as before described.

The two ends of the wire held in either end of grippers 95 are twisted together by the following-described mechanism: Fastened to shaft 90 is arm 98, which, as said shaft is making its revolution, engages with arm 143, which is loose on shaft 138. The pivotal points of the two being different it will be seen that arm 143 will be released from the control of arm 98 when the two shall have reached the point X, (see Fig. 18,) and arm 143, by means of coiled spring j , springs back to stop 145, and in so doing, by means of pawl 144, causes ratchet-wheel 142 and gear 141, both attached to shaft

138; to make a quarter-turn, which gives gear 140, one-fourth the size, attached to sleeve 146, a complete turn. Sleeve 146 is loose on shaft 90 and has a bearing in frame 148. Gear 97, being attached to sleeve 146, receives a complete turn simultaneously with gear 140, which causes gear 96 and grippers 95, both attached to shaft 102, to revolve quite rapidly, and as they revolve the ends of the wire being held in either end of grippers 95 are twisted together. The number of times that it is desired to twist the wire may be regulated by the comparative size of gears 96 and 97. As grippers 95 are making their last turn, the projecting end of cam 100 engages with pin 104, fastened to gear 97, and although they are both going in the same direction the cam 100 moves in a smaller circle and more rapidly than pin 104, and by pressing against the said pin the projecting end is forced down to a parallel position with grippers 95, which, being released, spring open by means of spring 103, releasing the two ends of the wire which have been twisted together, and completing the binding operation, and leaving grippers 95 in their normal position transversely across the packer and open at both ends.

147 is a pawl which prevents gear 97 from turning in an opposite direction to that intended for it to turn. The relative positions of the grippers 95 and grippers on arms 94 are parallel, grippers 95 being below and shorter than grippers 94' and 94", so that when the end of the wire is held in grippers 94' it allows grippers 95 to make their necessary revolutions without encountering the wire.

I am aware that prior to my invention folding and wrapping machines have been made wherein a folding-blade and two revolving rollers are used to accomplish the various folds. I therefore do not claim such a combination, broadly.

My invention may be used in the manner described, or it may be attached to a combined perfecting, printing, and folding machine, or any of the well-known makes of folding-machines now in use, by gearing it to such a machine in a suitable manner and allowing the paper to be carried, by means of tapes, from such a machine into my improved folding, wrapping, addressing, and binding machine.

What I do claim, and desire to secure by Letters Patent, is--

1. In a folding, wrapping, and addressing machine, the combination, with a chain of addressing-plates and mechanism, substantially as set forth, for feeding the same, of a plunger cut away to admit said chain, a pawl operating the feed mechanism, and means, substantially as herein specified, for reciprocating the plunger, substantially as described.

2. The combination, with the feed-board 2 cut away centrally upon its edge, of the drop-rolls 4, the roll 3, cut away centrally, the arms 5, carrying the drop-rolls, the arm 5', and cam-disk 6, substantially as described.

3. The combination of a series of upper and

lower endless tapes, as 8 14, moved continuously by tape wheels or rollers, with a pair of cutting-cylinders, as 19 20, coacting to sever a wrapper from a wrapper-web, associate it with a partly-folded paper, and convey the two onward in the manner as shown, and for the purpose as specified.

4. The combination, with rollers 29 and 30, of segment-wheels 31, paste-wheels 32, fountain 33, the jaws 45 and 46, and means, substantially as described, for operating the same, whereby the partly-folded wrapper is supplied with paste and the paper with its wrapper is then turned, substantially as described.

5. The combination, with the jaws 45 and 46 and the traveling tapes by which the partly-wrapped paper is carried, of the shaft 35, gears 39 and 40, the ratchet 41, lever 43, pawl 42, and slotted guides 44, substantially as described.

6. The combination of jaws 45 and 46 and their operating mechanism with an upper and lower set of tapes, as 28 34, operated to receive a partially wrapped and pasted paper and wrapper, turn the same over, and press down the flap to the main wrapper in the manner as shown, and for the purpose as specified.

7. The addressing-chain 62, composed of links having flexible connection, one of said links being provided with an extension, 69, substantially as described.

8. In combination with a folding and wrapping mechanism, an addressing-chain, as 62, inking-roller 121, sprocket-wheels 60, and plunger 51, coacting to impart to a folded or wrapped newspaper or periodical an address operated in the manner substantially as shown, and for the purpose as specified.

9. The combination of arms 52, plunger 51, with opening N, sprocket-wheels 60, arm 67, and pawl attached, ratchet-wheel 68, cam 65, and pawl 64, operated in the manner substantially as described to impart to an addressing-chain a step-by-step motion in the manner as shown, and for the purpose as specified.

10. The combination of link 69, tooth 71, drum 70, cam 73, lever 74, bolt 75, and endless chain 78, operated automatically to bring into operation a binding mechanism, in the manner substantially as shown, and for the purpose as specified.

11. A pair of twisting-grippers, as 95, in combination with cam 100, friction-wheel 80, and arm 81, operated in the manner as shown, and for the purpose as specified.

12. The combination of arm 81, grippers 94', 94", cam 110, twisting-grippers 95, shears 99, cam 100, and friction-wheel 80, operated to deposit in grippers 95 simultaneously the end of wire 83 and the main wire at the point where it is to be severed, and sever the same, leaving the two ends of the new wire formed in grippers 95, in the manner substantially as shown, and for the purpose as specified.

13. The combination of grippers 95, gears 96 and 97, arms 98 and 143, gears 140 and 141, ratchet-wheel 142, pawl 144, and spring j, operated to give to grippers 95 a rotary motion

and twist the wire, in the manner substantially as shown, and for the purpose as specified.

14. The combination of gear 97, pin 104, cam 100, and spring 103, operated to open grippers 5 95, in the manner substantially as described, and for the purpose as specified.
15. The combination of bars 106, pawl 108,

arm 81, and cam 109, operated to open bars 106, in the manner substantially as described, and for the purpose as specified.

GUSTAVUS S. ALDEN.
